UNITED STATES PATENT OFFICE.

FRANK DE BARBADILLO, OF BALTIMORE, MARYLAND, ASSIGNOR TO EDWARD J. REILLY, OF BALTIMORE, MARYLAND.

SHOE-POLISHING DEVICE.

1,142,679.

Specification of Letters Patent. Patented June 8, 1915.

Application filed December 2, 1914. Serial No. 875,094.

To all whom it may concern:

Be it known that I, FRANK DE BARBADILLO, a citizen of the Republic of Peru, residing at Baltimore, in the State of Maryland, have 5 invented certain new and useful Improvements in Shoe-Polishing Devices, of which the following is a specification.

The present invention relates to improvements in shoe polishing devices involving a 10 shoe supporting element and guide means for a polishing cloth used in conjunction therewith.

The essence of the invention lies in the 15 production of an article susceptible of being very cheaply manufactured and possessing peculiarly arranged cloth guiding members which not only facilitate the polishing of the shoes but are so formed as to enable the cloth to be operated properly, particularly 20 at the toe and heel portions of said shoe.

A still further object in view is to provide 25 cloth guiding members of the character above mentioned having adjustable connection with the shoe supporting member so that the device may be used efficiently in connection with shoes of different widths, thus insuring polishing action of the cloth on the side portions of the shoe both when used in connection with shoes of narrow and 30 wide lasts.

These and such other objects as may hereinafter appear are attained by the novel construction, combination and arrangement of parts to be hereinafter specifically described 35 and claimed.

Reference will now be had to the accompanying drawing forming a part of this specification, wherein:—

Figure 1 is a perspective view of a device 40 constructed in accordance with my invention, and Fig. 2 is a plan view of the same, with the extremities of the shoe supporting member broken away to show more clearly the interlocking connection between the cloth 45 guiding members and the same. Fig. 3 is a view of the polishing device showing the shoe in position for being polished.

Referring to the drawing it will be observed that this device consists only of two 50 main elements, namely the shoe supporting member or plate A which is preferably of wood, though obviously capable of being made of any other desired material, and the cloth guiding members B and C extending laterally from said shoe support. These 55

latter members are identical in configuration and construction and are interlocking connected with the support by having their extremities seated in transverse grooves D formed in each end of the shoe supporting 60 plate A. This affords a sliding connection for each of the cloth guiding members so that the same may be extended or contracted according to the width of the shoe which is to be operated upon, such extension being 65 clearly shown in Fig. 2 of the drawings in dotted lines while the contracted form is disclosed by full lines. Obviously the guide members to be extended need only to be pulled laterally and the form of each of said 70 members is such that it may be pulled at one end more than at the other end if the form of the shoe is such that the arrangement is desired or necessary. The guide members B and C are formed of very heavy wire material of more or less resilient character and when disposed in the end grooves maintain their adjusted position by reason of frictional contact with the shoe support. 75

The plate or support A is preferably 80 formed to have the general configuration of the shoe, and the guide members are also bent intermediate their length to conform substantially to the shape of said plate. The main portions of the guide members of 85 course normally are disposed in spaced relation to the sides of the support A and each of said members is bent so as to provide a toe extension or loop B', C' at the forward extremity and with a heel loop or extension 90 B'', C'' at its rear portion. One of the main difficulties in articles of a similar character to the present invention has been the proper manipulation of the polishing cloth at the toe and heel of the shoe and 95 these cloth guiding members have been constructed to overcome such difficulties.

The use of the invention will be apparent, it being understood that a narrow strip of cloth is employed for polishing purposes, 100 said strip being passed upwardly through the space between one cloth guiding member and the shoe support, over the shoe or foot placed upon said support and downwardly through the space between the opposite cloth 105 guiding member and the support. By reciprocating the cloth back and forth the polishing action is performed.

It is to be distinctly understood that I do not wish to be confined to the exact configu- 110

ration and form of the device as shown in the drawings since in these particulars changes may be made within the scope of the appended claims and without departing 5 from the spirit of said invention.

Having thus described the invention, what I claim as new is:—

1. In a shoe polishing device of the class described, the combination of a shoe support or plate formed with transverse grooves at its end edges, and a cloth guiding member at each side of the support having its terminals recurved for forming toe and heel guide elements and for seating in the 15 grooves aforesaid, said guide members being movable laterally in the grooves with respect to each other and the shoe support adapted to abut with each other to limit movement in one direction.
2. As a new article of manufacture, a shoe polishing device of the class described

comprising a plate having its extremities transversely grooved and a cloth guiding member slidably disposed at each side of the support and comprising a length of metal 25 or wire bent at its rear extremity to form a heel loop and having said rear extremity bent laterally for sitting longitudinally in the groove at the rear end of the shoe support, said metal being bent also at its forward end portion into a toe loop projecting 30 forwardly of the shoe support, the forward extremity of said metal being bent laterally from said loop for sitting longitudinally in the groove at the forward end of said shoe 35 support.

In testimony whereof I affix my signature in presence of two witnesses.

FRANK DE BARBADILLO.
